C. H. CASPAR

CARBURETOR

Filed April 15, 1920

UNITED STATES PATENT OFFICE.

CHARLES H. CASPAR, OF PHILADELPHIA, PENNSYLVANIA.

CARBURETOR.

Application filed April 15, 1920. Serial No. 374,066.

To all whom it may concern:

Be it known that I, CHARLES H. CASPAR, a citizen of the United States, and a resident of the city of Philadelphia, county of Philadelphia, and State of Pennsylvania, have invented certain new and useful Improvements in Carburetors, of which the following is a specification, reference being had to the accompanying drawing, forming a part hereof.

10 My invention relates to carburetors for use with internal combustion engines more especially of the automotive type, among the principal objects of the invention being to provide a carburetor adapted for use with fuel of different grades and particularly the less volatile or lower grades of fuel. A further object of the invention is to provide in a carburetor means for supplying liquid fuel under any desired pressure and temperature

15 preparatory to carburetion and means for preheating the fuel prior to its introduction to the current of incoming air. A still further object of the invention is to provide in a carburetor means whereby the fuel may be

20 retained under pressure prior to vaporization; to provide means for automatically varying the amount of fuel admitted to the stream of incoming air in conformity with the velocity of the latter, as well as manually

25 operable means for increasing the proportion of fuel to the air.

Still further objects of the invention are to provide a carburetor so constructed as to eliminate liability of flooding and to provide

30 means whereby any danger arising from increase of fuel pressure in the fuel chamber is eliminated, while additionally, the invention includes all of the other objects and novel features of construction and arrangement hereinafter more particularly illustrated or described.

In the accompanying drawing I have shown a carburetor constructed in accordance with one form of my invention, the single figure being a vertical central section of the device with certain parts shown in elevation.

The carburetor shown in the drawing comprises a fuel chamber 1 surmounted by a mixing chamber 2 in turn surmounted by a throttle chamber 3 adapted for connection to the intake manifold of an internal combustion engine. The mixing chamber is provided with a lateral air intake 4 flaring out-

wardly from its inner to its outer end. The 55 several chambers are conveniently secured together by the bolts 5 and 6 and the air intake to the side of the mixing chamber by the bolt 7.

The fuel chamber is provided with a jacket 60 8 and also with a tubular member 9 extending through an aperture 10 in the lower part of the mixing chamber and projecting upwardly in the latter, while a plug 11 of any suitable insulating material provided with exterior threads 14 and including lead wires 12, is screwed into the lower wall of the fuel chamber so as to extend upwardly therein, the upper ends of the wires 12 being connected with a suitable heating element 13 65 70 extending in the tubular member 9. The lower end of the plug projects beyond the wall of the chamber and carries terminals 16 provided with binding screws 17 and connected with the lower ends of the lead wires 12. Through these terminals connections may be made with a suitable source of current supply.

The fuel chamber may be provided with a drain connection 18 having a valve 19 and 80 with a connection 20 having a check valve 21, this connection beyond the check valve leading to a hand pump 21' conventionally illustrated which may be used when desired to increase the pressure in the fuel chamber. For conducting the fuel to the chamber the latter is also provided with a connection 22 having a check valve 23 and leading to the main fuel supply while ports 24 and 25 are arranged in the jacket 8 for connection to the pipes through which a heating medium such as hot water or gases from the exhaust may be supplied thereto.

During the normal operation of the engine the liquid fuel is drawn from the fuel chamber through a valve port 46 in the upper part of member 9 and hereinafter more particularly referred to which, when the engine is at rest, is closed by a valve 45. In order to relieve any excessive rise in pressure within the fuel chamber due to heating of the contents thereof or other cause, suitable means are provided conveniently comprising a screw threaded plug 26 positioned in an opening in the mixing chamber wall, 105 arranged to extend into the mixing chamber and to be locked in any desired position by a lock nut 27. This plug is provided with a

central bore 28 in which one end of the valve stem 29 of a valve 30 is adapted to slide longitudinally, the other end of valve stem extending into a transverse bore 31 formed adjacent the upper end of the tubular member 9. The latter is provided with a vertically extending passage terminating in a restricted orifice 33 at its upper end, the orifice and passage connecting the interior of the member 9 with the interior of the mixing chamber. The valve stem 30 terminates in a tapered valve 34 extending across and arranged to normally close the passage 32 and also with a collar 35 between which and the inner end of the plug is positioned a coil spring 36 which constantly urges the valve 34 to closed position. Thus on the generation of an excessive pressure within the fuel chamber, the valve and valve stem are forced to the left when viewed as in the drawing to open the passage 32 and vent the chamber, adjustment of the plug 26 in and out being operative to regulate the pressure under which the valve will open.

Means are provided for utilizing the stream of air drawn through the inlet tube 4 to effect the admission to the mixing chamber from the fuel chamber of an amount of fuel proportionate to the amount of air drawn into the former. For this purpose a spider 37 is mounted adjacent the outer end of the tube to support coaxial therewith a sleeve 38 in which is threaded an adjusting screw 39 which may be locked in position by a lock nut 40 while at the inner end of the tube and conveniently integral therewith is another spider 41 having a central interiorly threaded hub 42. A propeller shaft 43 having threads 44 cooperative with those in the interior of the hub 42 is provided, the inner end of this shaft carrying a tapered or conical valve 45 cooperative with the port 46 provided in the upper part of the tubular member 9, the other end 47 of the shaft being arranged to slide within a socket 48 in the adjusting screw 39. Rigidly secured to the shaft is a collar 49 to which is connected one end of a coil spring 50, the other end of which is connected to the adjusting screw in such manner that rotation of the latter within the sleeve 38 will wind up or unwind the spring and thereby increase or decrease the tendency of the spring to rotate the shaft, the lock nut 40 being adapted to hold the screw in any desired position of adjustment. Between the threads 44 and collar 49 the shaft is preferably provided with a suitable slot 51 adapted to cooperate with a key on the hub 52 of a propeller 53 in such manner that the hub can slide longitudinally of the shaft but is constrained to rotate therewith. The propeller comprises a plurality of blades 54 secured to the hub and arranged in suitable angular relation

with the axis thereof in such manner that the air sucked past the propeller will tend to rotate the latter, and in turn the shaft, in a direction to move the propeller shaft outwardly through coaction of the threads 44 with the hub 42 and thus raise the valve 45 from its seat, the torque exerted by the propeller on the shaft being in a direction opposite to that exerted by the spring.

Means are provided for manually moving the propeller longitudinally of the shaft when desired, said means preferably comprising a lever 55 pivoted to a bracket 56 conveniently formed integral with the tube 4, one end of the lever having a fork 57 engaging pins 58 carried by the hub 52 while the other end of the lever is connected to one end of a spring 59 the other end of which is connected to the casing 3, a control rod 60, also connected with the same end of the lever, leading to any convenient position for manual operation, the arrangement of these several parts being such that the lever may be readily moved from the position shown in full to that shown in dotted lines or to any intermediate position and thus cause a corresponding movement of the propeller.

The throttle chamber 3 is provided with the usual throttle 61 with its shaft 62 and operating arm 63 connected with a control rod 64 leading to any convenient position. The arm 63 is provided with stops 65 and 66 adapted to contact with a stop pin 67 carried by the casing, a stop screw 68 being arranged in the stop 66 for contact with the pin 67 in the usual manner.

In the operation of a carburetor of the form hitherto described the fuel is fed through the connection 22 into the fuel chamber 1 and maintained therein under pressure substantially equal to that within the fuel tank but the pressure in the fuel chamber may be increased when desired through the hand pump cooperative with the connection 20. When a current is passed through the heating coil 13 the latter will heat the fuel in the chamber thus increasing its capacity for vaporization, the heat supplied from the jacket also contributing to this result, and in case the pressure in the fuel chamber induced thereby should become excessive, the valve 34 will be raised from its seat and the pressure suitably relieved.

When the motor is rotated and suction thereby induced in the mixing chamber, a stream of air is drawn into the latter through the tube 4 which, owing to the shape of the tube, increases in velocity as it passes therethrough. Assuming the propeller to be in the position shown in full lines, in which it is normally maintained by the spring 59, the initial action of the air is to cause a slight rotation of the propeller,

and in turn the shaft, against the torque of the spring 50 thereby raising valve 45 slightly from its seat and permitting the fuel to flow from the fuel chamber into the moving stream of air. As the suction in the manifold is increased through the speeding up of the motor, the air is drawn more rapidly and in greater volume through the tube 4 which tends to turn the propeller further and further in a direction to open the valve 45 and thus increase the flow of fuel in correspondence with the increase in the flow of air. Additionally, the longitudinal pressure of the air against the propeller tends to simultaneously move the latter inwardly along its shaft and thus progressively bring it into zones in which the air contacts with the blades with increased velocity, thus additionally increasing the torque of the propeller and correspondingly raising the valve 45. It will thus be observed that under normal conditions of operation an increase in the suction exerted by the engine causes, if it may be so termed, a dual effect on the propeller, namely, an increase in its rotation due to the rapidity with which the air is drawn into the mixing chamber and an additional increase through the bodily inward movement of the propeller by which it is brought to a zone in which the air is moving at greater speed than adjacent the mouth of the tube 4, both of these effects tending to lift the valve 45 from its seat and correspondingly increase the flow of fuel.

Moreover, if it be desired at any time to increase the relative quantity of fuel in respect to the amount of air which would be normally drawn into the motor at a given motor speed, or, in other words, to enrich the mixture, the propeller may be moved longitudinally inward along its shaft from any point thereon by actuation of the control rod 60 thereby bringing the propeller into a zone in which the velocity of the incoming air is higher than its initial velocity when it enters the inlet tube, thus increasing the torque of the propeller to lift the valve 45 further from its seat than would be the case were the propeller in the position on the shaft which it would automatically assume under the influence of the incoming air alone. Conversely the mixture may be made "leaner" at any time while the engine is running by moving the propeller outwardly along its shaft from the position it may naturally have assumed under the influence of the inspirated air. It will of course be understood that irrespective of the position of the propeller on the shaft the force exerted on the propeller blades by the air will cause the latter to rotate only to a point at which such force is balanced by the torque of the spring 50 and that as the suction of the

engine increases or decreases or as the propeller is moved in and out along the shaft under a constant suction, the angular position of the propeller will be correspondingly altered, thereby effecting a corresponding opening or closing of the valve 45 to increase or decrease the flow of fluid to the mixing chamber, and further that at any time proportions of the air and fuel in the mixture may be altered by moving the propeller on the shaft without varying the volume of the inspirated air thus avoiding the usual choking frequently encountered in other types of carburetors wherein the volume of air is curtailed to enrich the mixture.

While I have herein described and illustrated with considerable particularity a preferred embodiment of my invention, I do not thereby desire or intend to limit myself in any manner to any particular details of construction or arrangement of parts as suitable changes and modifications may be made therein if desired without departing from the spirit and scope of the invention as defined in the appended claims.

Having thus disclosed my invention what I claim as new and desire to protect by Letters Patent of the United States is:

1. In a carburetor the combination of a fuel chamber, a mixing chamber, a valve controlling the admission of fuel from the fuel chamber to the mixing chamber, an air inlet communicating with the mixing chamber and of decreasing cross sectional area as it approaches the chamber, and means adjustable in said tapering air inlet for varying the position of said valve in correspondence with the flow of air through the inlet.

2. In a carburetor, the combination of a fuel chamber, a mixing chamber, a valve controlling the admission of fuel from the fuel chamber to the mixing chamber, an air inlet communicating with the mixing chamber and decreasing in diameter as it approaches thereto, a shaft extending in the inlet and connected with said valve, means for moving the shaft longitudinally when rotated, a propeller rotatable with and longitudinally slideable on the shaft, yieldable means for normally maintaining said propeller adjacent the mouth of the inlet, and adjustable means associated with said shaft for yieldingly resisting the torque of the propeller on the shaft when air is drawn through the inlet.

3. In a carburetor, the combination of a fuel chamber and a mixing chamber, of an air inlet communicating with the latter and of decreasing cross sectional area as it approaches thereto, a valve controlling the admission of fuel from the fuel chamber to the mixing chamber, a shaft connected with said valve, a propeller rotatable with and

slidable longitudinally on the shaft, yield- other than that which the propeller would able means for normally maintaining said normally assume under the influence of the propeller adjacent the larger end of the inspired air. ¹⁰
inlet, yieldable means for resisting the torque of the propeller on the shaft, and manually operable means for holding the propeller in any desired position on its shaft

In witness whereof, I have hereunto set my hand this 13th day of April, 1920.

CHARLES H. CASPAR.
